the point of grease utilization, such as the differential or transmission of a motor vehicle. Thereafter the plunger 17 is depressed manually into the can body until all of the grease is expelled, 5 the position of the nozzle 15 at the periphery of the can head aiding in the assurance of complete drainage.

Attempts to refill the can after use are substantially impossible and economically impractical, due to the fact that withdrawal of the plunger 10 from its depressed position will cause disengagement of the sealing element 19 from its seat 18, and the general inability to properly reposition the plunger 17 in a plane at right angles to the 15 longitudinal axis of the can to obtain the snug and leakproof fitting of the parts as originally assembled.

As shown by Figs. 3 and 5, we have provided additional means to prevent re-filling of the can 20 after use by means which destroy the can head. Thus the modified plunger 17' which is otherwise similar to the construction of plunger 17, above set forth and is operative in a like manner, is provided with a knife blade 23 secured to its 25 inner face adjacent to its center as at 24. As the plunger 17' is depressed during the dispensing operation the knife 23 destroys the can by cutting a slit in the head 12, and in addition to thus destroying the can is an indicator of complete dispensing of its contents.

We claim as our invention:

1. A grease dispenser comprising a body adapted to contain grease, a head fixedly secured thereto, a spout extending from said head adjacent its peripheral edge and provided with a terminal removable closure, the said closure being adapted to be replaced during dispensing operation by a delivery conduit engageable to said spout, a bottom closure slidably positioned within 35 said body and adapted to act as a plunger and 40 slidably completely to said head and provided

with a handle for manual actuation thereof, an inner peripheral surface seat formed on the face of said plunger, and a packing element loosely positioned in said seat in sealing engagement with said body.

2. A grease dispenser comprising a body adapted to contain grease, a head fixedly secured thereto, a spout extending from said head, a bottom closure slidably positioned within said body and adapted to act as a plunger and provided with a handle for manual actuation thereof, an inner peripheral seat formed on the face of said plunger, and a packing element of substantially rectangular cross-sectional area positioned in said seat in sealing engagement with said body with one surface exposed to the contents thereof, the said packing element comprising porous expansible material adapted to be swelled and the sealing action thereof enhanced by means of liquid pressure.

3. A grease dispenser comprising a body adapted to contain grease, a head fixedly secured thereto, a spout extending from said head adjacent its peripheral edge and provided with a terminal removable closure, a bottom closure slidably positioned within said body and adapted to act as a plunger and provided with a handle for manual actuation thereof, an inner peripheral seat formed on the face of said plunger, and a packing element positioned in said seat in sealing engagement with said body with said bottom closure element, the said packing element having a surface area exposed to the interior of said body in a plane substantially parallel to the face of said plunger comprising sponge rubber adapted to be swelled and the sealing action thereof enhanced by means of grease contained in said body during the dispensing thereof.
